UNITED STATES PATENT OFFICE.

MILTON D. HAYS, OF OVERTON, PENNSYLVANIA.

GRAVITY WATER MOTOR.

Application filed October 31, 1924. Serial No. 747,093.

This invention relates to a gravity water motor.

The object of the invention is to provide a water motor having a wheel which is strong, simple, and in which the buckets of the wheel may be removed and others substituted with a minimum amount of labor.

In the accompanying drawings Figure 1 is a side elevation water wheel used in a water motor; Figure 2 is an end elevation of the same; Figure 3 is a cross sectional view through the same on the line 3—3 Figure 1; Figure 4 is a vertical sectional detail through a portion of the water wheel, taken on the line 4—4 Figure 2, and illustrating the method of attachment of the buckets to the supporting shaft and the supporting rods of the wheel; and Figure 5 is a detail view in side elevation of one of the buckets 20 of the wheel.

The water wheels 8 are mounted on a shaft 9 which comprises a tubular portion 9^a, and end portions 9^b. The end portions 9^b have portions 10, which extend outwardly from the tubular shaft 9^a, and form axles or trunnions for the shaft. Formed integral with the portions 10 are extensions 32 which extend into the tubular shaft 9^a at which end thereof, and around which the shaft 9^a may be shrunk. Mounted on the shaft 9^a are end plates 33. Passing through the end plates 33 are rods 34, which are disposed in a circular manner adjacent the periphery of the plates. The extremities of these rods are screw threaded, and are held in position by means of nuts 35. Surrounding the shaft is another group of rods 36, which are held in position by means of nuts 37, and which are arranged in a group concentric with the shaft and with the outer group formed by the rods 34.

The wheel 8 comprises a plurality of bucket sections 38 extending longitudinally of the shaft; and each of such bucket sections comprising a plurality of buckets 39.

Each bucket 39 is formed simply as a curved plate, and is shown as substantially semicircular in cross section. At one end thereof each bucket is provided with a pair of hooks or tongues 40 which embrace one of the outer rods 34 of the wheel, and is secured thereto by means of a bolt 41. On its outer surface each of the buckets has a pair of lugs or ears 42, which receive one of the inner group of rods 36, and which is secured thereto by means of a bolt 43. At its inner extremity each of the buckets is deformed to

provide a hook 44, which engages in a slot 45 in a tubular shaft 9^a. It will be noted that the portions 32 of the solid shaft 9^b have therein annular grooves 46, to permit the entrance of the tongues or hooks of the buckets at such points.

With this wheel a damaged bucket may easily be removed and replaced with a new one without replacing other buckets or portions of the shell, and without taking down the wheel as a whole. As many bucket sections may be carried by a single shaft as may be desirable with consideration of the strength of the shaft and the weight of water which will act upon the wheel. If desired, two or more wheels constructed in this manner may obviously be aligned longitudinally, and provided with common terminal shafts or axles to give a water wheel of great length.

It should be noted further that each of the buckets 39 is curved in order that it may receive a relatively great weight of water, and may retain this water as long as possible during each revolution of the wheel; and also in order that the resistance offered to the entry of each bucket into the column of water may be minimized.

What I claim is:

1. For use in a water motor a water wheel comprising a central shaft, end plates on said shaft, a plurality of bars disposed parallel to said shaft and arranged for attachment to the end plates, and a plurality of mutually independent buckets secured to said shaft and to said bars.

2. For use in a water motor a water wheel comprising a hollow slotted shaft, end plates on said shaft, a plurality of bars disposed parallel to said shaft and arranged for attachment to the end plates, and a plurality of mutually independent buckets each having lugs arranged to engage in the slots of said shaft and lugs arranged to secure the bucket to said bars.

3. For use in a water motor, a water wheel comprising a central shaft, end plates on said shaft, a plurality of bars disposed parallel to said shaft and arranged for attachment to the end plates, and a plurality of mutually independent buckets secured to said shaft and to said bars, said buckets being substantially semicircular in cross section.

4. For use in a water motor, a water wheel comprising a hollow slotted shaft, end plates on said shaft, a plurality of bars disposed parallel to said shaft and arranged for attachment to the end plates, and a plurality of mutually independent buckets each having lugs arranged to engage in the slots of said shaft and lugs arranged to secure the bucket to said bars.

tachment to the end plates, and a plurality of mutually independent buckets each having lugs arranged to engage in the slots of said shaft and lugs arranged to secure the bucket 5 to said bars, said buckets being substantially semicircular in cross section.

5. For use in a water motor, a water wheel comprising a central shaft, end plates on said shaft, two concentric series of bars disposed 10 parallel to said shaft and arranged for attachment to the end plates, and a plurality of mutually independent buckets each secured to said shaft and to a bar of both concentric series.

15. 6. For use in a water motor, a water wheel comprising a central shaft, end plates on said shaft, two concentric series of bars disposed parallel to said shaft and arranged for attachment to the end plates, a plurality of 20 mutually independent buckets secured to said shaft, and spaced attaching lugs on each of the buckets for providing attachment of the bucket to a bar of both concentric series.

7. For use in a water motor, a water wheel 25 comprising a central shaft, end plates on said shaft, a plurality of bars disposed parallel to said shaft and arranged for attachment to the end plates, and a plurality of mutually independent buckets each secured to said shaft and to two of the bars.

30. 8. For use in a water motor, a water wheel comprising a central shaft, end plates on said shaft, a plurality of bars disposed parallel to said shaft and arranged for attachment to the end plates, and a plurality of mutually independent buckets each secured to said shaft and to two of said bars, said buckets being substantially semicircular in cross section.

35. 9. For use in a water motor, a water wheel 40 comprising a central shaft, end plates on said

shaft, a plurality of bars disposed parallel to said shaft and arranged for attachment to the end plates, a plurality of mutually independent buckets secured to said shaft, and spaced attaching lugs on each of the buckets for providing attachment of the bucket to two of the bars, said buckets being substantially semicircular in cross section. 45

10. For use in a water motor, a water wheel comprising a central shaft, end plates on said shaft, a plurality of bars disposed parallel to said shaft and arranged for attachment to the end plates, a plurality of mutually independent buckets secured to said shaft, and spaced attaching lugs on each of the buckets for providing attachment of the bucket to two of the bars. 50 55

11. For use in a water motor, a water wheel comprising a hollow slotted shaft, end plates on said shaft, a plurality of bars disposed 60 parallel to said shaft and arranged for attachment to the end plates, and a plurality of mutually independent buckets each having thereon a lug arranged to hook into a slot into the shaft, each of said buckets being attached to two of the bars. 65

12. For use in a water motor, a water wheel comprising a hollow slotted shaft, end plates on said shaft, a plurality of bars disposed 70 parallel to said shaft and arranged for attachment to the end plates, a plurality of mutually independent buckets each having thereon a lug arranged to hook into a slot in the hollow shaft, and spaced attaching lugs 75 on each of the buckets for providing attachment of the bucket to two of the bars.

In witness whereof, I hereunto set my hand.

MILTON D. HAYS.
